UNITED STATES PATENT OFFICE.

ERNEST V. SHALEN, KARL R. OLOFSSON, AND BROR L. OLOFSSON, OF DORCHESTER, MASSACHUSETTS, ASSIGNEES TO KAKAS BROS., INC., OF BOSTON, MASSACHUSETTS, A CORPORATION OF MASSACHUSETTS.

STRETCHING APPARATUS.

Application filed March 16, 1922. Serial No. 544,353.

To all whom it may concern:

Be it known that we, ERNEST V. SHALEN, a subject of the King of Sweden, and resident of Dorchester, in the county of Suffolk and State of Massachusetts (whose post-office address is 179 Minot Street, Dorchester, Massachusetts), and KARL R. OLOFSSON, a subject of the King of Sweden, and BROR L. OLOFSSON, a citizen of the United States, 5 and residents of Dorchester, in the county of Suffolk and State of Massachusetts, have invented an Improvement in Stretching Apparatus, of which the following description, in connection with the accompanying drawings, is a specification, like letters on the drawings representing like parts.

Our present invention relates to devices for use in holding, stretching and drying pelts, skins and the furs of fur-bearing animals, particularly small fur-bearing animals as a preliminary step in subsequent use and manufacture in the making of garments.

In prior stretching devices of this general type, numerous attempts have been made to 25 provide a wire or metal frame on which the pelt or skin could be stretched, but such prior devices have been unsatisfactory in actual use, because of the difficulty in handling them, time required to apply, attach, hold 30 and stretch the pelt, injury resulting to the fur of the pelt, and similar objections, so that in actual use, it is preferable to employ a series or set of boards, on which the pelts are applied, stretched and tacked 35 in shape.

Our present invention is directed to obviate the difficulties of prior wire or metal stretching appliances and to be as acceptable and capable in actual use to the present practice of using the boards, while also eliminating the danger and injury to the pelts by doing entirely away with tacks or other securing means which will in any way deteriorate or damage the fur.

45 We have combined in a spring form of metal holder and stretcher, attaching and adjustable apparatus which enables great speed of operation, affords rigidity and uniform tension on the skins while drying, is 50 capable of a wide range of adjustability and therefore can handle small and large skins up to the limit of its length, and permits a quick, efficient and positive locking of the stretching devices.

Further features and advantages and 55 novel details of construction will be herein-after more fully pointed out and claimed.

Referring to the drawings, illustrating a preferred embodiment of our invention,

Fig. 1 is a plan view of our improved 60 metallic stretcher illustrating a skin of substantially the largest length and capacity for which the apparatus is adapted;

Fig. 2 is a side view of the apparatus;

Fig. 3 is a cross-sectional view on the line 65 3—3 of Fig. 5;

Fig. 4 is a cross-sectional view on the line 70 4—4 of Fig. 5; and

Fig. 5 is an enlarged side view of the adjustable cross-bar. 75

In carrying out our invention any suitable length of metal and diameter of the same can be employed. Preferably we would provide a set of three or possibly four frames of varying sizes to take care of the 75 entire range of skins and pelts for any particular work, each one of these frames being capable in itself to handle, hold and stretch a considerable range of pelts. We also prefer to use a round spring wire, forming the 80 same as illustrated in Fig. 1, with the sides 1 and 2 springing from the apex 3, and in a curved form with the shorter arm 2 formed with an eye-loop 4 and the longer arm 1 having its endmost portion bent transversely as shown at 5, passing through the loop 4 in the short arm 2 and ending in a short upturned end 6 which acts as a stop and partly as a handle. The inner surfaces of 85 these sides 1 and 2 are provided with a series 90 of notches as indicated at 10, 10. These notches may be formed in any suitable manner, but preferably are simply recesses filed or formed on the inner surfaces of the side arms 1 and 2, substantially as shown. 95

Applied to the sides 1 and 2 is a sliding cross-bar 12 having thereon means to hold and retain the tail portion of the pelt to effect the longitudinal stretching and also having means to lock the cross-bar 12 in 100 adjusted position, both longitudinally and cross-wise with relation to the sides 1 and 2. For this purpose the cross-bar 12 has formed therein slots 13 and 14 of substantial length and sufficient diameter to span the sides 1 and 2, to slide freely thereover. In order to firmly and positively lock the cross-bar 105 12 to the sides 1 and 2, both longitudinally

for stretching the skin lengthwise, and laterally for stretching the skin widthwise, we attach to the extreme ends of the cross-bar 12 at 16 and 17, notched locking levers 5 18 and 19 respectively, each lever having a series of notches 20 of appropriate form and diameter to catch over the sides 1 and 2 and engage the notches 10, holding the sides 1 and 2 both extended to the limit of the 10 stretching capacity of the pelt 21 being applied, while also holding the same stretched longitudinally, as will be readily appreciated. These locking levers are also fitted with a small finger clip or catch 22 to facilitate releasing or raising the levers and remove the tension of the cross-bar 12 and sides 1 and 2 after the skin is stretched and it is desired to remove the same.

It is necessary to apply to the tail piece 20 of the pelt being stretched, a fastening means which will firmly retain the same and yet will not injure the fur. As these pelts when applied to the stretching frame are green and very slippery it has heretofore 25 been extremely difficult to secure the tail piece with any non-slipping fastening device which would not injure the fur. In the use of a board where tacks were employed the fur was injured but slightly, but 30 in our invention we have devised a novel fastening means which does not perforate the fur in any way, which will hold it securely, firmly and rigidly, and enable the entire skin to be stretched longitudinally 35 when applied to the frame. This fastening device comprises a channel or U-shaped member 25 adapted to partially enclose the cross-bar 12 when the fastener 25 is moved downwardly into fur engaging position, thus clamping the fur firmly and in an 40 S-shaped path around the top of the cross-bar 12. This clamping member 25 has a pair of rearwardly extending lugs 26 and 27 pivoted to the cross-bar 12 at 28, and at 45 the forward part is formed to receive a notched catch 30, as clearly shown in Fig. 3. a portion of the channel or arm of one side being removed to constitute the cooperating catch engaging member 33. This catch 30 is 50 preferably pivoted at 35 to the cross-bar 12 as also clearly illustrated in Figs. 3 and 5. In the operation of our improved stretching frame, the operator holds the same by the curved or bottom portions, viewing Fig. 55 1, fits the pelt 21 over the apex 3 and pulls the pelt into approximate position, thereupon attaching the cross-bar to the tail 36

of the pelt 21, clamping the tail piece firmly to the cross-bar by swinging the fastener 25 downwardly and retaining the same in position by engaging the catch 30, so that the teeth therein will engage and hold the end portion 33 of the fastener 25. Thereupon the operator expands the sides 1 and 2 and simultaneously moves the cross-bar 12 rearwardly to stretch the pelt longitudinally, and when in desired adjusted position, the operator snaps downwardly the arms 18 and 19 which engage the sides 1 and 2 in the adjacent notches 10, thus holding the pelt 70 and frame in extreme stretched position to which the same has been adjusted, both widthwise and lengthwise. The peculiar configuration of the fastener 25 cooperating with the cross-bar 12 giving a firm, rigid 75 and yet non-marring grip on the tail of the pelt while holding the same in stretched position and yet can be instantly released after the pelt is cured and it is desired to remove the same. Similarly the locking 80 arms 18 and 19 can be quickly lifted by engagement with the finger clips 22 and the tension from the pelt instantly released both cross-wise and longitudinally.

In using our improved frame a pelt can 85 be applied as quickly as has been possible on tapered boards, can be secured thereto much more rigidly, is useful in supplying a constant spring tension capable of contraction with the drying of the pelt, and is 90 capable also of a wide range of sizes, and furthermore the entire frame can be cleaned, steamed, sterilized or the like without injury, if desired. For this purpose we desire to make the frame of non-corrosive 95 spring metal of any suitable composition, construction, strength and size.

Our invention is further described and defined in the form of claim as follows:

A skin stretching frame of the kind described, comprising movable side arms 100 united at an apex, a cross-bar slidable upon said side arms, and capable of being locked thereto, in combination with means on said cross-bar to hold and secure a portion of a 105 pelt applied to the frame, the means on the cross-bar to lock the same to the sides comprising a pair of pivoted notched locking arms.

In testimony whereof, we have signed our 110 names to this specification.
